(57) **CLAIM**

The ornamental design for an adjustable lounge chair, as shown and described.

DESCRIPTION

FIG. 1 is a top front perspective view of the adjustable lounge chair, showing the new design;

FIG. 2 is an alternative top front perspective view of the adjustable lounge chair;

FIG. 3 is a front elevational view of the adjustable lounge chair thereof;

FIG. 4 is a rear elevational view of the adjustable lounge chair thereof;

FIG. 5 is a left side elevational view of the adjustable lounge chair thereof;

FIG. 6 is a right side elevational view of the adjustable lounge chair thereof;

FIG. 7 is a top plan view of the adjustable lounge chair thereof; and,

FIG. 8 is a bottom plan view of the adjustable lounge chair thereof.

The broken lines shown in the drawings illustrate portions of the article that form no part of the claimed design.
